UNITED STATES PATENT OFFICE.

GEORGE H. MOON, JR., OF PRESCOTT, IOWA.

MAIL DEVICE.

1,012,410.

Specification of Letters Patent.

Patented Dec. 19, 1911.

Application filed May 16, 1911. Serial No. 627,395.

To all whom it may concern:

Be it known that I, GEORGE H. Moon, Jr., a citizen of the United States, residing at Prescott, in the county of Adams and 5 State of Iowa, have invented new and useful Improvements in Mail Devices, of which the following is a specification.

This invention relates to improvements in mail bag delivering and receiving apparatus, and the object of the invention is to provide a simple and effective device of this character, whereby a mail bag may be delivered from a passing train to a station post or from the station post to the train 15 or simultaneously delivered and received by both the post and the train.

Another object of the invention is to provide an apparatus of this class whereby mail may be delivered and received without 20 danger of injury to the said mail.

With the above, and other objects in view, which will be more apparent as the nature of the description progresses, the invention resides in the novel construction 25 and arrangement of parts hereinafter fully described and claimed.

In the accompanying drawings there has been illustrated a simple and approved embodiment of the improvement, and in which 30 drawings—

Figure 1 is a side elevation of the apparatus, illustrating both the mechanism provided by the station and the mechanism provided by the car. Fig. 2 is a top plan 35 view of the same. Fig. 3 is a central longitudinal sectional view taken through the train apparatus. Fig. 4 is an end elevation of the station device. Fig. 5 is a sectional view taken through the station holder and 40 adjacent the top thereof.

In the accompanying drawings the numeral 1 designates an ordinary mail car, and the numeral 2 designates a station crane which is arranged in close proximity 45 with the tracks upon which the car passes. The mechanism carried by both the car and the station crane are substantially similar, the station crane comprising a post 3 having an extending top portion 4 which is provided with suitable braces 5, one of 50 which supports a downwardly extending arm 6.

The numeral 7 designates the delivery cylinder for the station crane. This cylinder 55 preferably has one of its ends cone shaped as at 8, and arranged between the

said cone shaped ends is a resilient cushion 9. The opposite end of the cylinder 7 is open, and is normally closed through the medium of a hinged door 10. This door 10 is retained upon the cylinder through 60 the medium of a suitable lock 11.

The numeral 13 designates a track which is arranged upon the top of the cylinder 7 which extends the entire length thereof. 65 The track 12 comprises a pair of spaced members, each arranged a suitable distance above the cylinder and each having one of its ends connected with the said cylinder. The track is adapted to be engaged by a plurality of rollers 13 carried by the arm 6. The rollers are preferably arranged in spaced relation with each other, so that the casing 7 is at all times directly balanced 70 upon the station crane.

The numeral 14 designates the receiving member of the station crane. This receiving member is supported upon a suitable standard 15, the latter being preferably 75 constructed of some partially resilient material. The receiver 14 is provided with a flaring mouth 15 and the said receiver is provided adjacent the said mouth with a suitable door 16.

This door is formed with a spring hinge 17, the same being provided 80 upon an offset portion connected with the door proper and the said spring is adapted to normally force the door 16 to a closed position within the receiver. The door is sustained in a normally open position 85 through the medium of a spring catch 18. This catch is provided with the upwardly extending operating member and the said catch is adapted to be contacted by the delivery member 19 carried by the train when 90 the said member is positioned within the receiver in the manner which will be presently set forth. The end of the receiver opposite to that of its flaring mouth 15 is cone shaped, and said cone shaped end is 100 provided with a flexible cushion 20, the latter adapted to partially overcome the force of the delivery member 19. The upper portion or face of the receiver 14 is provided with a longitudinally extending cut 105 away portion 21, the latter adapted to serve as means whereby the rollers 13 will be free to travel through the said receiver without contacting the same when the deliverer 19 is inserted within the receiver 14.

The car mechanism is, as above stated, substantially similar to that heretofore de-

scribed excepting that the delivery member is supported upon rollers 21' which are secured to the said car. The receiving member 22 is substantially similar to that of the receiving member 14, but the said receiving member is also sustained upon the car. It is to be understood that the delivery member of the station crane alines with the receiving member of the car, and that the receiving member of the crane also registers with the delivery member of the car, so it will be noted that when a car is passing the station it will deliver the mail from the cylinder 19 to the receiver 14 and that the receiver 22 of the said car will catch and hold the cylinder 7 of the station crane.

Having thus fully described the said invention, what I claim is:—

20 1. In a mail bag catcher and deliverer for cars, a bag holding cylinder, said cylinder being provided with a track, the car being provided with an arm having rollers engaging the track, and a receiving station 25 provided with a receiving member adapted to engage and remove the cylinder from the track.

2. In a mail bag catcher and deliverer for cars, a bag receiving cylinder, said cylinder having one of its ends open and provided with a door, the opposite end of the cylinder being cone shaped, the said cylinder being formed with a longitudinally extending track, the said car being provided with a downwardly extending arm, rollers upon the frame, and a delivery station having a receiver adapted to engage the said deliverer and to remove the same from its track.

40 3. A mail bag delivering apparatus for a car, said deliverer comprising a cylinder having one of its ends opening and a door for said opening, the opposite end of the said cylinder being cone shaped, resilient bumper members within the cone shaped end of the cylinder, the said cylinder having its face formed with a longitudinally extending track open at one of its ends, the said car being formed with a downwardly

extending arm having rollers adapted to engage with the track, all substantially as and for the purpose set forth.

4. The combination with a railway car, of a mail delivering cylinder provided with a longitudinally extending track, the car being provided with rollers adapted to engage the said track, a station post, said station post being provided with a receiving cylinder having a flared mouth and resilient cushions within the cylinder, and the upper face of the said cylinder being open to receive the rollers of the car, substantially as and for the purpose set forth.

5. In a device for the purpose set forth, the combination with a receiving and a delivering apparatus, said delivering apparatus comprising a cylinder having one of its ends cone shaped and its opposite end open, means for holding the cylinder, the receiving member also comprising a cylinder having an open flared mouth, said cylinder being provided with a spring cushioned door, a latch for sustaining the door in a normally open position and said latch adapted to be contacted by the cylinder when the same is inserted within the receiver to close the door.

6. In an apparatus for the purpose set forth, a station provided with a post having an offset portion formed with a depending arm, rollers carried by the said arm, a delivery cylinder provided with a track mounted upon the said rollers, a standard upon the station, a receiving cylinder carried by the standard, said receiving cylinder being provided with a flared mouth, the opposite end of the receiving cylinder being cone shaped and having resilient cushions, a door for the receiver, and a spring latch for normally sustaining the door in its open position, substantially as and for the purpose set forth.

In testimony whereof I affix my signature in presence of two witnesses.

GEORGE H. MOON, JR.
